(57) **CLAIM**

The ornamental design for a muffler, as shown and described.

DESCRIPTION

FIG. 1 is a first perspective view of an ornamental design for a muffler, according to the invention.

FIG. 2 is a front view of a muffler of FIG. 1.

FIG. 3 is a back view of a muffler of FIG. 1.

FIG. 4 is a left view of a muffler of FIG. 1.

FIG. 5 is a right view of a muffler of FIG. 1.

FIG. 6 is a top view of a muffler of FIG. 1; and,

FIG. 7 is a bottom view of a muffler of FIG. 1.

The shading and contour lines in FIGS. 1-7 are for illustrative purposes only and form no part of the claimed design.

1 Claim, 7 Drawing Sheets

FIG. 1

FIG. 2

FIG. 3

FIG. 4

FIG. 5

FIG. 6
